UNITED STATES PATENT OFFICE.

LESTER E. HICKOK, OF MECHANICSBURG, PENNSYLVANIA, AND CHARLES T. McCUE, OF HARTFORD, CONNECTICUT; SAID HICKOK ASSIGNOR OF ONE-HALF OF HIS RIGHT TO FRANK E. WILCOX, OF MECHANICSBURG, PENNSYLVANIA.

VEHICLE-GEAR.

SPECIFICATION forming part of Letters Patent No. 734,706, dated July 28, 1903.

Application filed October 28, 1902. Serial No. 129,081. (No model.)

To all whom it may concern:

Be it known that we, LESTER E. HICKOK, a resident of Mechanicsburg, Cumberland county, State of Pennsylvania, and CHARLES T. McCUE, a resident of Hartford, in the county of Hartford and State of Connecticut, citizens of the United States, have invented new and useful Improvements in Vehicle-Gears, of which the following is a specification.

Our invention relates to vehicle-gears, the object being the production of a gear comprising few parts which shall be very simple in construction, which shall have the lower fifth-wheel member and central bearing-boss integral with the axle, which shall preferably have the upper fifth-wheel member, reach-irons, and spring-plate integral, which shall be very strong and not liable to become de-ranged, and which withal shall constitute a superior means for performing the requisite functions of a perfect gear.

Our invention consists in certain novelties of construction and combinations and arrangements of parts hereinafter set forth and claimed.

The accompanying drawings illustrate an example of the physical embodiment of our invention constructed according to the best mode we have so far devised for the practical application of the principle.

Figure 1 is a top plan of the gear with the spring, spring-stays, and reaches removed. Fig. 2 is a front view in elevation with the spring and spring-stays in place. Fig. 3 is a perpendicular section in elevation of Fig. 2, taken on a line corresponding to line *xx*, Fig. 1. Fig. 4 is a cross-section in elevation of the complete gear, taken at the king-bolt and to one side of the antirattler. Fig. 5 is a top plan view of the spring-plate, reach-irons, and upper fifth-wheel member. Fig. 6 is a top plan view of the axle, axle-boss, and lower member of the fifth-wheel. Fig. 7 is a view in perspective of the brace and antirattler-spring.

Referring to the several figures of the drawings, the letter A designates the metallic axle, which in this instance is curved in cross-sec-

tional outline; B, the lower circular member 50 of the fifth-wheel forged integral with the axle and having its free ends projecting beyond the same; C, the perforated cylindrical bearing-boss integral with the axle, projecting above the same and in the rear thereof; 55 D, a recess in the under surface of the boss; E, a spring-plate or plate to serve as a bearing for the spring; F, a recess in the upper surface of the plate, whereby the lower leaf of the spring may frictionally engage the bearing-surface of the plate encircling the recess; G, a recess in the lower surface of the plate to receive the heads of the bolts and hide them from view; H, the downwardly-inclined ends of the plate which connect with the upper fifth-wheel member; I, a perforated bearing-lug at the rear of the plate containing in its lower surface a circular recess within which is located the bearing-boss of the axle; J, a flange surrounding the recess; K, a brass 70 washer; L, bolt-holes through the plate; M, perforated leaves of an elliptical spring; N, bolts and nuts; O, the upper circular member of the fifth-wheel; P, perforated lugs; Q, the reach-irons integral with the spring-plate; 75 R, the raised perforated bearings upon the reach-irons; S, the reaches; T, the spring-stays, perforated and engaging the raised bearings; U, the perforated heads of the spring-stays; V, the bolts uniting the reach-irons and spring-stays; W, a brace; X, the tapering head of the brace; Y, the perforated recessed end of the brace, within which the lower member of the fifth-wheel is seated and moves; Z, a perforated leaf-spring having 85 concavo-convex ends in cross-section which bear against the lower surface of the lower member of the fifth-wheel and holds it in frictional contact with the upper member; Z', bolts; Z², the king-bolt, and Z³ is a nut 90 on the king-bolt.

The method of assembling the parts is obvious upon an inspection of the drawings and need not be set forth.

From the foregoing description it is clear 95 that we have produced a vehicle-gear which fulfills all the conditions enumerated as the purpose and object of our invention. It will

be noted that the spring rests directly upon the spring-plate, obviating the use of a head-block, the reach-irons are located above the upper member of the fifth-wheel, the spring-
5 stays stiffen the combined parts, and the cylindrical boss and head of the brace secure the axle firmly and relieve the king-bolt of excessive strains.

In physically embodying our improvements
10 it is of course to be understood that modifications may be introduced at the will of the manufacturer. We have shown the upper member of the fifth-wheel integral with the reach-irons and spring-plate and located below the reach-irons, and we prefer this construction; but the upper member may be secured in place by other means than welding. The spring-plate is recessed upon its under surface, so that the heads of the bolts will be
15 hidden. This recess may, however, in some cases be omitted. All such and other changes we shall consider as unsubstantial and as falling within the scope of our invention.

What we claim as new, and desire to secure by Letters Patent, is—

1. The combination in a vehicle-gear, of a metallic axle having the lower circular member of the fifth-wheel and the cylindrical bearing-boss integral therewith; a spring-
30 plate with reach-irons, and a perforated lug or boss integral therewith; an upper circular fifth-wheel member having lugs, P, and secured to the ends of the spring-plate and beneath the top surfaces of the reach-irons; a brace with a perforated head and a perforated and recessed end secured to the lugs, P; and a king-bolt.

2. The combination in a vehicle-gear, of a metallic axle having the lower member of the

fifth-wheel and the cylindrical bearing-boss 40 integral therewith; a spring-plate, reach-irons, perforated lug, and upper member of the fifth-wheel formed integral; spring-stays secured to the reach-irons; a lower brace having a head at one end engaging the axle- 45 boss, and its rear end secured to the upper member of the fifth-wheel; and a king-bolt.

3. The combination with a vehicle-gear, of a lower brace having one end secured to the axle, and the other end secured to the upper 50 member of a fifth-wheel and confining the lower member of the fifth-wheel; and a spring bearing against the lower member and holding it in frictional contact with the upper member.

4. The combination with a vehicle-gear, of an upper fifth-wheel member having perforated lugs, a brace with a recess for the lower member of the fifth-wheel, a spring with ends bearing against the lower member, and bolts 60 securing the several parts together.

5. The combination with a vehicle-gear having upper and lower circular fifth-wheel members, of an axle provided with a perforated cylindrical boss, C, in the rear thereof; a 65 spring-plate with a recessed and perforated lug, I, fitting over the boss, C, a lower brace with a perforated head at one end and secured to the upper member of the fifth-wheel at the other end; and a king-bolt.

In testimony whereof we affix our signatures in presence of two witnesses.

LESTER E. HICKOK.
CHARLES T. McCUE.
